WINDOW CONSTRUCTION

Alvin H. Gottesleben, Detroit, Mich., assignor to Twin Pane Corporation, Detroit, Mich., a corporation of Michigan

Filed Feb. 28, 1962, Ser. No. 176,228

3 Claims. (Cl. 20—56.5)

This invention relates to a window construction and more particularly to that type of window construction which requires no manual application of putty to the window after the glass has been installed.

It is a further object to provide a window construction which is particularly adapted to the use of a double pane combination which provides a thermal insulation.

There are a number of window installations today which still utilize the wood frame which is adapted for standard glazing wherein a recess receives a pane of glass which is puttied in place.

It is an object of the present invention to provide a double pane glass assembly which can be moved in to a wood frame and which will automatically lock and seal in said frame.

It is a further object to provide a thermal pane construction in which the entire unit can be handled as a single member.

It is a further object to provide as a part of a combination an extruded frame section for the window unit which is designed for use with a double pane unit.

Other objects and features of the invention relating to details of construction and operation will be apparent in the following description and claims.

Drawings accompany the disclosure and the various views thereof will be briefly described as follows:

FIGURE 1, a sectional view of a window assembly constructed according to the present invention.

FIGURE 2, an exploded view showing the double pane frame unit and the receiving frame.

FIGURE 3, an enlarged view showing the manner in which the window unit is locked into the frame.

FIGURE 4, a perspective view of a corner of the window unit assembly.

Having reference to the drawings, in FIGURE 1 a primary or outer wood frame 10 has a top run 12 and a bottom run 14 with side runs 16. The bottom and the side runs are each provided with a recess 20 which consists of an open-sided groove extending around the outside of the frame. As shown in FIGURE 1, about $\frac{1}{4}$ " inside the edge of the wood frame is a small groove 22 which extends the entire length of the bottom and side runs in the groove 20. This is primarily simply a marking groove for the use of glazing materials but it can be used to cooperate with a locking member of the assembly to be described. The devices shown in FIGURES 2 and 3 eliminate this groove since it is not essential to the operation of the device. The wood from which the window frames are made is usually a relatively soft wood; and as will be described later, the locking element for the assembly can gouge into this wood and become firmly locked.

The upper run does not have the groove 20 but is provided with a narrow surface slot 24 which has its inner surface spaced inwardly from the outside of the window frame the same distance as the inner wall of the groove 20. The window assembly unit comprises a secondary frame, three sides of which are formed of a channel section shown best in FIGURE 3.

This channel section, preferably of extruded plastic, has a base 30 with two side walls 32 and 34. The side wall 34 continues below the base section in a short wall 36. On the bottom of the base 30 on the same side as

2

wall 32 is a small channel section which has re-entrant grooves provided by flanged portions 38 and 40.

The channel described can be used for the lower run and the two side runs of the glass assembly insert. The upper plastic channel is preferably formed (FIGURE 1) with a base section 42 having side walls 44 and 46 with the small double channel section 48 adapted to project upwardly into the groove 24 of the upper run 12 of a window frame.

Small closed channels 50 of a light material, such as aluminum, are formed into a frame member which creates a spacer between two glass panes 52 and 54 lying inside the walls 32 and 34 of the bottom and side sections of a frame and the walls 44 and 46 of the upper section. The section of the spacer is narrower at the outside edge 55 so that contact with the glass is spaced inwardly from the edges. Thus, with proper dimensioning, as shown in FIGURE 1, the glass panes are snugly inserted between the walls of the secondary frame members, which are preferably formed of a resilient plastic material, and the outer walls of the spacer elements 50.

The corners of the plastic secondary frame members can be readily secured together and sealed by a plastic solvent or a heat seal, creating an insulating air pocket between the two panes 52 and 54. Inserted in the channel formed between members 38 and 40 is a locking strip which is composed of a base 60 and a resilient locking flange or blade 62.

This material can be formed of a light metal material which is pushed into the channel formed by the members 38 and 40. When the two sides and the bottom of the assembled window unit are fitted with these elements, the window unit within the secondary frame can be installed into the frame by tipping the upper double flange 48 into the groove 24 of the top run 12 of the frame and pushing the remainder of the window unit into place in the groove 20. This motion causes an inward flexing of the flanges 62 and when the edges reach the groove 22, these flanges snap into place in these grooves as shown in FIGURE 1.

In the embodiment shown in FIGURES 2 and 3, it will be noted that the locking blade 62 has a squared off edge which creates a sharp corner 64. This sharp edge 64 readily moves into the frame 14 in the direction of the arrow shown in FIGURE 2 because of the angle of the blade 62 but again, due to this angle, the edge digs into the wood so that it will not move out of the frame but rather will simply gouge into the wood and lock itself securely in place.

In the installation of the assembled frame into the sash, it is preferable that a suitable sealing material be extruded around the frame, for example, in the area A in the corner of the recess 20 of FIGURE 2 and in the area B in the corner between the wall 36 and the base 30. Thus, as the frame is moved into the place, it seals both on the inner surface and the outer surface.

The window assembly is, therefore, securely held in place; and it will be noted that the slightly resilient plastic flanges 36 lie over the outside of the window frames beyond the grooves 20 so that the entire unit is weather sealed in the frame. Thus no additional caulking or putty need be applied after the setting of the glass to provide a tight window assembly which, in addition to being weatherproof, is also a thermal insulation protection for the area in which the window is finally mounted.

The assembly of the glass into the frame is thus accomplished very rapidly and the assembly is locked into place until such time as the panes might be broken and it is necessary to replace them. The assembly units are such that the installation of the glass can be accomplished either in the shop or at the place in which the window is being installed. The glass assembly is a complete

unit in itself which can be readily transported independently of the frame.

I claim:

1. A window combination assembly comprising an outer frame of relatively soft material such as wood having an opening therein with walls lying at substantially right angles to the plane of the frame, said frame having upper, lower, and side runs, the upper run having a groove spaced from an external surface of said run, a glass assembly unit associated with said frame comprising a secondary frame of semi-resilient plastic material having upper, lower, and side runs, each of said runs of said secondary frame having spaced inwardly extending flanges to receive and enclose the periphery of a double pane assembly, a single outwardly extending flange on said lower and side runs of said secondary frame overlying a portion of an external surface of the outer frame directly adjacent the opening therein, the upper run of said secondary frame having an outwardly extending flange positioned in the groove of the upper run of said outer frame, a substantially V-shaped locking strip on the outer periphery of the lower and side runs of said secondary frame having one locking leg of the V extending outwardly at an angle to the secondary frame and in a direction toward the external surface of the frames, means for slidably fastening the other leg of said locking strip flat against said outer periphery of said secondary frame, the free edge of said outwardly extending locking leg being engaged with the walls of the opening in said outer frame to lock the two frames in rigid assembly.

2. A window assembly for use with an outer frame of relatively soft material such as wood, said outer frame being provided with a recess for accommodating said assembly, said recess having respective walls generally perpendicular and parallel to the plane of said outer frame, said assembly comprising a pair of spaced glass panes mounted in a secondary frame of semi-resilient plastic material having upper, lower, and side runs, one of said runs having an integral internal flange extending inwardly of said secondary frame and abutting an exposed surface of one of said panes, said one run having integral external flanges extending inwardly and outwardly from said run, said inwardly extending external flange abutting an exposed surface of the other of said panes, said outwardly extending external flange overlying an external surface of said outer frame when said secondary frame is accommodated therein, means integral with said one run forming a re-entrant groove thereon, a substantially V-shaped locking strip slidably received in said re-entrant groove, said locking strip having one leg directly adja-

5 10 15 20 25 30 35 40 45 50

cent said one run and the other leg extending outwardly at an angle to said secondary frame in a direction toward said external surface of said frames, the free edge of said other leg being adapted to engage said perpendicular wall of said outer frame when said assembly is accommodated therein to lock said assembly in said outer frame with said internal flange of said one run abutting said parallel wall of said outer frame.

3. In combination an outer frame of relatively soft material such as wood, said outer frame being provided with a recess accommodating a window assembly, said recess having respective walls generally perpendicular and parallel to the plane of said outer frame, said assembly comprising a pair of spaced glass panes mounted in a secondary frame of semi-resilient plastic material having upper, lower, and side runs, one of said runs having an integral, internal flange extending inwardly of said secondary frame and abutting an exposed surface of one of said panes and said parallel wall, said one run having integral external flanges extending inwardly and outwardly from said one run, said inwardly extending external flange abutting an exposed surface of the other of said panes, said outwardly extending external flange overlying an external surface of said outer frame, said one run having a re-entrant groove formed thereon by a pair of flanges extending outwardly from said one run, each of said last mentioned flanges being substantially continuous along said one run in a direction between said side runs, a substantially continuous locking strip slidably received in said re-entrant groove, said locking strip being substantially V-shaped with one leg directly adjacent said one run and the other leg extending outwardly at an angle to said secondary frame in a direction toward said external surface of said frames, the free edge of said other leg being engaged with said perpendicular wall of said outer frame to lock said assembly in said outer frame.
